THOMAS H. BENSEL, OF CAMDEN, NEW JERSEY.

DESIGN FOR A MATCH-BOX.

No. 38,788.

Specification for Design.

Patented Sept. 10, 1907.

Application filed July 12, 1907. Serial No. 383,537. Term of patent 3½ years.

To all whom it may concern:

Be it known that I, THOMAS H. BENSEL, a citizen of the United States, residing at Camden, in the county of Camden and State of New Jersey, have invented a new, original, and ornamental Design for Match-Boxes, of which the following is a specification, reference being had to the accompanying drawing, forming a part thereof.

The figure is a perspective view of the match box showing my new design.

I claim

The ornamental design for the match box, as shown.

THOS. H. BENSEL.
